UNITED STATES PATENT OFFICE.

WILLIAM S. LANEY, OF BALTIMORE, OHIO.

PUMP.

SPECIFICATION forming part of Letters Patent No. 247,663, dated September 27, 1881.

Application filed July 21, 1881. (No model.)

To all whom it may concern:

Be it known that I, WILLIAM S. LANEY, a citizen of the United States, residing at Baltimore, in the county of Fairfield and State of Ohio, have invented certain new and useful improvements in Pumps; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

This invention relates to double sucker or lift pumps, and has for its object to provide an improved stock or casing for the invention described in Letters Patent granted to me and numbered 242,140, bearing date May 31, 1881.

It consists in a single tube or casing composed of an under cylinder, an upper cylinder arranged laterally to and above the plane of the upper end of and in a vertical line parallel with the lower cylinder, an intermediate cross-pipe bent to connect the upper end of the lower cylinder with the lower end of the upper cylinder, a discharge end connected to and bent laterally from the upper end of the upper cylinder to a vertical line midway between the two cylinders and then carried vertically upward, and provided with means for holding the operating-lever, the operating-lever pivoted to the top of the discharge end of the casing, and the piston-rods connected to the operating-lever on opposite sides of its pivotal connection and carried downward into the cylinders through stuffing-boxes placed in the elbows or bends at the upper ends of the cylinders, and provided with the necessary pistons, all of which will be hereinafter fully described.

In the drawings, Figure 1 is a side elevation. Fig. 2 is a vertical section; and Fig. 3 is a portion of the upper end of the casing, showing a side view of the discharge-spout.

This improved pump-stock is composed of the four principal parts or sections, A, B, C, and D, which, when united, as shown, make a continuous tube or casing adapted for a double sucker pump of the class shown in my Patent No. 242,140.

C is the under or lower cylinder, to the upper end of which is connected the cross-pipe

D, which is bent laterally to form an elbow, D', vertically above the cylinder. On the upper side of the elbow there is a piston-rod opening, e, which is provided with a stuffing-box, e'.

The cross-pipe D is bent laterally and vertically, as shown, so that it connects with the lower end of the cylinder B, as shown.

The cylinder B is placed laterally from and is arranged in a vertical line parallel with the vertical line drawn through the cylinder C, and it is set above the plane of the upper end of the lower cylinder.

The discharge end A of the pump-stock has its lower end connected to the upper end of the cylinder B, and is bent laterally into an elbow, A', on the upper side of which, and in line with the vertical center of the cylinder, there is formed a piston-rod opening, f, which is provided with a suitable stuffing-box, f'. The end A is carried laterally from the end of the cylinder B to a point or line midway between vertical lines extended upward from the cylinders, and is then bent into a vertical position and extended upward to a sufficient length, so that the operating-lever c can be pivoted on its top, as shown. The upper end is covered by a cap, A², which is provided with lugs or jaws, to which the handle is pivoted.

c is the handle, which is pivoted on the upper end of the section A, and is so arranged as to have its pivotal points h and i arranged on opposite sides of the pipe A and immediately over the cylinders B and C, and it is connected to the piston-rods a and b by links a' and b', as shown. The piston-rods a and b are carried down through the stuffing-boxes f' e' into the cylinders, and have fixed to their lower ends the pistons a² b².

d is a rim or collar placed on the upper end of the cylinder B, and may be used to hold the stock in place on a suitable framing.

k is a pipe connected to the lower end of the cylinder C when it is desired to reach the water in deep wells.

Suitable check-valves may be arranged at the points marked l and m, and, if desired, a valve could be inserted in the upper end of cylinder C, at n.

This pump-stock is constructed in the several parts described, which parts may be de-

tached for any desired purpose. It is a strong, durable, and cheap pump-stock, easy to handle and set in any well.

Having thus described my invention, what I claim, and desire to secure by Letters Patent, is—

The improved pipe or tube for double-acting lift or suction pumps, composed of an under cylinder, an upper cylinder arranged laterally to and above the plane of the upper end of and in a line parallel with the lower cylinder, an intermediate cross-pipe bent to connect the upper end of the lower cylinder with the lower end of the upper cylinder, a discharge-pipe connected to and bent laterally from the upper

end of the upper cylinder to a line midway between the two cylinders and then carried vertically upward, the stuffing-boxes arranged at the elbows or bends in the pipe, and the necessary means for holding the operating-lever and piston-rods in proper relative positions to the cylinders, substantially as set forth.

In testimony whereof I affix my signature, in presence of two witnesses, on this 13th day of July, 1881.

WILLIAM S. LANEY.
